UNITED STATES PATENT OFFICE.

HENRY HOBART PERKINS, OF LAS VEGAS, TERRITORY OF NEW MEXICO.

SEAL-LOCK.

SPECIFICATION forming part of Letters Patent No. 340,351, dated April 20, 1883.

Application filed May 6, 1885. Serial No. 164,577. (Model.)

To all whom it may concern.

Be it known that I, HENRY HOBART PERKINS, a citizen of the United States, residing at Las Vegas, in the county of San Miguel and 5 Territory of New Mexico, have invented a new and useful Improvement in Seal - Locks, of which the following is a specification, reference being had to the accompanying drawings.

My invention relates to seal-locks; and it 10 consists in the improved construction and combinations of parts hereinafter fully described, and pointed out in the claims, whereby a strong, effective, and serviceable lock is provided, and one that may be manufactured and 15 supplied at a slight cost.

In the drawings, Figure 1 is a view in elevation showing my improved seal-lock applied. Fig. 2 is a view of the lock with the rear plate removed and showing the position 20 occupied by the parts when locked. Fig. 3 is a similar view to Fig. 2, but showing the device unlocked; and Fig. 4 is a detail view of the seal employed.

In the accompanying drawings, in which 25 like letters of reference indicate corresponding parts in all the figures, A represents the hasp, which is pivoted to the car-door. The free end of the said hasp is hooked, as shown at a, and is provided with the nib or projection b.

D represents a metal casing, which is composed of two parts or sections, the part d only being shown in the drawings, which are designed to be secured together by screws or 35 equivalent fastening, as shown.

E represents a tumbler, which is pivoted between the sides composing the casing D, and at the upper end thereof adjacent to an aperture or opening, e, in the upper end of the 40 casing, which aperture is provided for the admission of the hooked end of the hasp A, which hooked end is adapted to engage the lower end of the pivoted tumbler. It will be seen that as the tumbler is eccentrically pivoted—that is, at its upper end—that it will at all 45 times maintain a vertical position.

F represents a plate, which is pivoted near the lower end of the casing. The said plate F is provided with an upwardly-extending 50 hooked finger, H, which is adapted to bear

against the outer side of an extension, H', formed upon the tumbler E. The plate F is also provided with an extension, G, projecting upwardly, and adapted to bear against the inner side of the extension H' of the tumbler E. 55 It will thus be seen that a space, f, is formed by said hooked finger H and extension G, in which space the lower end of the extension H' works.

At the lower end of the plate F is provided 60 a downwardly-extending curved arm, J, which is adapted to work in an aperture or opening formed at the lower end of the casing, the movement of the said curved arm being limited by the side of the casing, as at g, so that 65 its free end can just clear the lower end of the casing sufficiently to admit a seal, c, or allow said seal to be placed upon the curved arm.

The operation is as follows: The hasp enters the aperture in the upper end of the casing 70 and bears against the inner side of the pivoted tumbler E, pushing it to one side. When the hooked end of said hasp has reached a point on a line with the lower end of the tumbler, the pivoted plate F forces said tumbler into 75 engagement with the hooked end of the hasp, the hooked finger H of the plate F bearing against the outer side of the extension H'.

It will be understood that previous to inserting the hooked end of the hasp into the 80 casing that the seal is placed upon the curved arm J. The extension H' of the tumbler E, when the device is locked, bears against the inner side of the hooked finger H, and thus holds the free end of the curved arm within 85 the casing, the seal fitting in recesses formed in the lower end of the casing.

To unlock the device, the seal must be first cut or broken, when the curved arm may be pushed upwardly by hand, which action causes 90 the extension G to bear against the inner side of the extension H' and remove the tumbler from engagement with the lower end of the hasp, and thus allow said hasp to be removed.

Having fully described my invention, what 95 I claim as new, and desire to secure by Letters Patent, is—

1. In a lock, the combination, with a casing, of a pivoted tumbler, a hasp adapted to be engaged by the tumbler to lock said hasp, a piv- 100

oted plate for locking the tumbler, and an arm on the lower end of said plate to receive a seal, substantially as set forth.

2. In a lock, the combination, with a casing, of a pivoted tumbler having an extension, a hasp adapted to be engaged by said tumbler, a pivoted plate having a hooked finger to bear against the outer side of the tumbler-extension, and an arm on the lower end of said plate to receive the seal, substantially as set forth.

In testimony that I claim the foregoing as my own I have hereto affixed my signature in presence of two witnesses.

HENRY HOBART PERKINS.
